CLAIM

I claim the ornamental design for a figure 8 shaped diffuser well, as shown and described.

DESCRIPTION

Design patent application, Ser. No. 29/179,346 filed Apr. 10, 2003. (Now pending).

Design patent application, Ser. No. 29/179,375 filed Apr. 10, 2003. (Now pending).

Provisional patent application, Ser. No. 60/464,664, filed Apr. 10, 2003. (Now pending).

FIG. 1 Top plan view.

FIG. 2 Bottom plan view

FIG. 3 Right elevation view

FIG. 4 Left elevation view

FIG. 5 Front elevation view; and,

FIG. 6 Back elevation view.

The broken lines shown in FIGS. 1 and 3–6 are for illustrative purposes only and form no part of the claimed design.
